UNITED STATES PATENT OFFICE.

HOWARD D. COLMAN, OF ROCKFORD, ILLINOIS, ASSIGNOR TO HOWARD D. COLMAN,
LUTHER L. MILLER, AND HARRY A. SEVERSON, COPARTNERS TRADING AS
BARBER-COLMAN COMPANY, OF ROCKFORD, ILLINOIS.

WINDER.

1,311,498.

Specification of Letters Patent. Patented July 29, 1919.

Application filed May 12, 1916. Serial No. 96,978.

To all whom it may concern:

Be it known that I, HOWARD D. COLMAN, a citizen of the United States, residing at Rockford, in the county of Winnebago and State of Illinois, have invented certain new and useful Improvements in Winders, of which the following is a specification.

One of the objects of this invention is to produce improved means for pressing the receiving yarn-mass against the driving drum.

Another object of the invention is to provide improved means for throwing the receiving yarn-mass out of operation upon the exhaustion of the yarn.

Another object is to provide means for automatically placing the detector mechanism in position to receive a new thread.

Another object is to provide improved means for restoring the receiving yarn-mass to operative position.

A further object is to provide means for preventing the receiving yarn-mass from being returned to operative position if the yarn mass has reached the desired diameter.

In the accompanying drawings, Figure 1 is a fragmental transverse vertical sectional view of a winder embodying the features of my invention. Fig. 2 is a fragmental view 30 of the means for pressing the yarn mass against the driving drum. Fig. 3 is a fragmental plan view showing a thread-guiding channel. Fig. 4 is a fragmental sectional view of the gaging means. Fig. 5 is a fragmental sectional view of a support which may be used in unwinding certain kinds of yarn masses. Fig. 6 is a fragmental front elevation of the winder. Fig. 7 is a view on the order of Fig. 1, but showing a different 40 position of the parts. Fig. 8 is a view showing the operation of the means for preventing the return of the receiving yarn-mass to operative position. Fig. 9 is a fragmental horizontal sectional view of the detector mechanism.

A winder embodying my invention may comprise any desired number of winding units each adapted to rewind yarn from successive bobbins *a* onto a tubular carrier *b* 50 to form a cylindrical cross-wound yarn mass or cheese *c*. The bobbin *a* may be supported in any suitable manner; for example, it may be non-rotatably supported for the drawing of the yarn off the tip of the bobbin, or it

may be rotatably supported for the unwinding of the yarn from the side of the bobbin. Herein is shown a bobbin-holder *A* which is substantially similar to the bobbin-holder shown in Patent No. 1,045,879 dated December 3, 1912.

The cheese is rotated through peripheral contact with a drum 1 fixed upon a continuously-rotating shaft 2. The drum 1 is provided with a peripheral cam-groove 3. When the cheese is in peripheral contact with the drum 1, the cheese is rotated and the yarn is rapidly traversed or guided back and forth.

In front of the cam drum 1 is a standard 4 having a bearing 5 at its upper end. (See 70 Fig. 7). A cheese-supporting lever 6 is provided upon one side and near one end with a pivot 7, which is mounted in the bearing 5, said pivot being rigid with the lever. At the end of the long arm of the lever 6 is 75 means for rotatably supporting the cheese, which means may be of any suitable character, as for example, that fully disclosed in application Serial No. 74,290 filed January 26, 1916.

Means is provided for pressing the yarn mass against the drum 1. Herein is shown a lever 8 pivoted at 9 to the standard 4. The upper end of the lever is rounded, as at 10, and has a notch 11 therein to receive a 85 lug 12 fixed to the pivot 7 of the lever 6. When the cheese is in contact with the driving drum 1 the lug 12 lies in the notch 11, and a spring 13 acting upon the lever 8 presses the cheese against the drum. At the 90 lower end of the lever 8 is a handle 8^a.

The means for automatically removing the cheese from the cam drum 1 when the yarn exhausts comprises a link 14 pivoted at its upper end to the short arm 15 of the lever 6, which link may be in the form of an elongated loop. A projection 16 on the standard 4 extends through the loop and prevents sidewise displacement thereof. 17 is a stop pin to limit forward movement of 100 the link 14. When the yarn exhausts, devices to be presently described swing the link 14 from its normal vertical position to a position within reach of a continuously-oscillating hook 18 which pulls the link 105 downward and thus throws the lever 6 from the position shown in full lines in Fig. 1 to that illustrated in Fig. 7, whereby the

cheese is withdrawn from the cam drum. The hook 18 is fixed upon a shaft 19 which may be rocked by any suitable means.

The means for swinging the link 14 within reach of the hook 18 comprises a vertical rock shaft 20 having fixed thereto two detector fingers 21 arranged to be yieldingly pressed against the running thread by means of a torsion spring 22 surrounding the shaft 20. 23 are stationary fingers constituting a grid against which the running thread is pressed by the detector fingers 21. 24 is an arm fixed to the detector shaft 20. When the thread exhausts, the shaft 20 is turned by the spring 22, whereby the arm 24 swings against the link 14 and carries said link within the range of action of the hook 18. Upon the next downward movement of the hook the link 14 is pulled downward so as to raise the cheese off the driving drum 1 and remove the lug 12 from the notch 11. As the lug 12 is being forced out of the notch 11, the lower portion of the lever 8 is caused to swing forward a little, but as soon as the lug has left the notch, the spring 13 swings the lever 6 against a stop 25 (Fig. 7), the action of the spring being yieldingly checked by a dashpot 26. The surface 10 is thus placed under the lug 12, whereby the cheese is prevented from dropping back into contact with the drum.

The means for returning the detector fingers 21 into position to receive a new thread comprises an arm 27 fixed to the shaft 20 in position to be engaged by the lever 8 when said lever is drawn rearwardly by the spring 13. In such movement of the lever 8, the parts carried by the shaft 20 are swung into the thread-receiving position shown by the dotted lines in Fig. 9. When the arm 24 is thus moved into the dotted-line position indicated in Fig. 9, the link 14 swings forwardly away from the hook 18. 28 (Fig. 3) indicates a sheet-metal structure secured to the machine frame and having a passageway 22^a through which the running thread extends. This passageway serves to guide the thread of a new bobbin into running position. 29 is a flaring entrance to said passageway. 30 is a hook located at one side of the entrance. The hook 30 keeps the thread of a new bobbin in position to be engaged by the detector fingers 21 as said fingers swing into operative position. Between the detector fingers and the passageway 28 the thread extends through a stationary guide or hook 31 (Figs. 1 and 9).

The means for preventing the cheese from being returned into contact with the drum 1 if the cheese has reached the desired diameter comprises a gage 32 which is pivoted to the machine frame at 33 in position to be touched and moved by a full cheese in the throwing-out movement of the latter. The

gage 32 is adjustably connected by means of a clamp screw 34 with an arm 35. The lower end of the arm 35 is yieldingly connected to the rear end of a link 36 by any suitable means, as, for example, a spring 37 connecting said link to a pin 38 set in the arm 35, said pin extending through an elongated opening 39 in the link. The forward end of the link is pivoted to a stop 40 which is pivoted to the machine frame at 41, said stop being arranged to lie behind the upper end of the lever 8 to prevent movement of said lever, as shown in Fig. 8. In the form herein shown, the gage 32 is constructed to serve as a counterweight which normally holds the stop 40 in the position shown in Fig. 7, in which position it does not interfere with movement of the lever 8.

Before replacing a full cheese with a cheese core *b*, the operator takes hold of the lever 6 and swings it forward into the position shown at *x* in Fig. 1. The lever 6 is supported in such position through contact of a lug 42 with the surface 43 of the lever 8, said lug being fixed to the pivot 7. When the lever 6 is thus swung forward, the upper end of the link 14 swings downwardly and rearwardly whereby the link is brought into contact with a fulcrum projection 44 (Fig. 1), the lower end of the link 14 being thus caused to swing forward out of reach of the hook 18.

The cheese cores *b* are returned from the warper creel with a small amount of yarn remaining thereon. The operator places such a cheese core upon the lever 6 while the latter occupies the position shown at *x* in Fig. 1; takes a bobbin *a*, finds the end thereon; unwinds a sufficient length of yarn on the bobbin; inserts the bobbin in the bobbin holder; places the bobbin thread within the hook 30 (Fig. 3); finds the thread end upon the cheese core; unites the bobbin thread and the cheese thread in any suitable way; swings the lever 6 into the position shown in Fig. 7, the cheese being held off the drum 1 by the lug 12 which rests upon the surface 10; and rotates the cheese by hand in the direction to wind up the thread, thus taking the slack out of the thread and preventing any kinks that may have been formed from being wound upon the cheese. The operator next draws the lever 8 forward to allow the detector fingers 21 to move into contact with the thread and to remove the surface 10 from beneath the lug 12 and bring the upper end of the wall 11^a of the notch 11 into contact with the lug 12. The operator then allows the spring 13 to draw the lever 8 slowly rearward. As the lug 12 passes down into the notch 11, the cheese descends upon the cam drum, the operator keeping the thread taut as it approaches the running position. After 130

the thread has been released and has assumed the running position, the operator releases the lever 8, thereby permitting the spring 13 to press the cheese against the cam drum. The upper end of the standard 5 4 is covered by a sheet-metal guard 45. The space between every two adjacent guards provides a passage 46 (Fig. 6) through which the new thread passes when moving rearwardly into contact with the cam drum. 10 As the new thread passes into running position, it springs into the hook 31.

When the thread of an incomplete cheese exhausts, the cheese is automatically moved 15 into the position shown in Fig. 7, and the operator repairs the break or ties on a new bobbin while the cheese occupies such position.

The winder is also adapted to unwind 20 defective yarn masses carried by cores *b*. Such yarn masses may be supported for the rewinding operation in any suitable manner. Herein is shown a stand 47 (Fig. 5), arranged to be placed upon the floor beneath 25 the bobbin holder A. Upon said stand is a stud 48 to fit into the tubular core *b* of a cheese placed in horizontal position upon the support 47. The thread from the cheese passes upwardly through the 30 space between guide wires 49 as indicated by the dot-and-dash line 50 in Figs. 1 and 6. The thread 50 also passes through a suitable tension device 51, under a guide 52 and to the detector fingers 21.

35 I claim as my invention:

1. A winder having, in combination, a 40 yarn-mass supporting lever, a projection fixed with relation to said lever, a lever pivoted between its ends, a spring tending to press the upper portion of the second lever against said projection, means for swinging the first lever to raise said projection above the second lever, said projection being arranged to rest upon the upper end of the second lever, and yarn-mass gaging means arranged to lock the second lever against movement in the direction to withdraw the upper end of the second lever from the projection.

50 2. A winder having, in combination, a 45 yarn-mass supporting lever, a projection fixed with relation to said lever, a lever pivoted between its ends, a spring tending to press the upper portion of the second lever against said projection, means for swinging the first lever to raise said projection above the second lever, said projection being arranged to rest upon the upper end of the second lever, and means to lock the second 55 lever against movement in the direction to withdraw the upper end of the second lever from the projection.

60 3. A winder having, in combination, a 65 yarn-mass supporting lever, a projection fixed to said lever, a lever pivoted between

its ends, said lever having a notch in its upper end to receive said projection, a spring tending to move the second lever, means for swinging the first lever to remove the projection from the notch, the projection 70 being arranged to rest upon the upper end of the second lever, and a handle on the second lever.

4. A winder having, in combination, a 75 yarn-mass supporting lever, a projection fixed with relation to said lever, a lever pivoted between its ends, a spring tending to press the upper portion of the second lever against said projection, and means for swinging the first lever to raise said projection above the second lever, said projection being arranged to rest upon the upper end of the second lever.

5. A winder having, in combination, a 85 yarn-mass support, a pivoted detector to detect exhaustion of the thread being wound, a spring-pressed lever operatively connected to said support, mechanism controlled by the detector for disconnecting the support from the lever, and an arm connected with 90 the detector and arranged to be engaged by the lever when the latter is disconnected from the support for moving the detector into thread-receiving position.

6. A winder having, in combination, a 95 yarn-mass support, a detector to detect exhaustion of the thread being wound, a spring-pressed lever operatively connected to said support, and mechanism controlled by the detector for disconnecting the support from the lever, said lever being arranged to move the detector into thread-receiving position.

7. A winder having, in combination, a 105 supporting frame, a drum rotatably mounted on the frame, a lever pivoted upon the frame, means on the lever for rotatably supporting a yarn mass with the periphery of the yarn mass in contact with the periphery of the frame, means for pivotally moving 110 the lever to withdraw the yarn mass from the drum, and means to lock the lever in withdrawn position.

8. A winder having, in combination, a 115 supporting frame, a drum rotatably mounted on the frame, a lever pivoted to the frame, means on the lever for rotatably supporting a yarn mass with the periphery of the yarn mass in contact with the periphery of the drum, means for pivotally moving the lever 120 to withdraw the yarn mass from the drum, a member movable into position to support the lever when withdrawn, and means for locking said supporting member.

9. A winder having, in combination, a 125 yarn-mass support; a yarn-mass rotator; means for moving the support to withdraw the yarn-mass from the rotator; a gage member arranged for contact with the yarn mass, when completed, in the withdrawal 130

of the latter; and means actuated by the gage member to lock the support in withdrawn position.

10. A winder having, in combination, a 5 yarn-mass support; a yarn mass rotator; means to place the support in operative relation to the rotator; and yarn-mass gaging means arranged to lock the placing means against actuation.

11. A winder having, in combination, a supporting frame, a drum rotatably mounted on the frame, a lever pivoted to the frame, means on the lever for rotatably supporting a yarn mass with the periphery of 15 the yarn mass in contact with the periphery of the drum, means for pivotally moving the lever to withdraw the yarn mass from the drum, a member movable into position to support the lever when withdrawn, a device to lock said supporting member, a member arranged to be moved through contact with the yarn mass when the latter is withdrawn, and a connection between the last-mentioned member and said locking member 25 for actuating the latter.

12. A winder having, in combination, a pivoted yarn-mass support, a stop for limiting pivotal movement of the yarn-mass support, and a yarn-mass gaging member movable through contact with the yarn-mass to place the stop in operative position.

13. A winder having, in combination, a yarn-mass rotator, a pivoted yarn-mass support adapted to hold the yarn-mass in operative relation to the rotator, and a gage 35 member arranged to be moved by contact with the yarn mass to limit movement of the yarn-mass support toward the rotator.

14. A winder having, in combination, a 40 supporting frame, a drum rotatably mounted upon the frame, a lever pivoted to the frame in front of said drum, means on the lever for rotatably supporting a yarn mass with the periphery of the yarn mass in contact with the periphery of the drum, means for moving the lever to withdraw the yarn mass from the drum, a gaging member pivoted to the frame rearwardly of the yarn mass in position for contact with the periphery of the yarn mass when the latter is withdrawn from the drum, and means controlled by said gaging member for preventing return movement of the yarn mass.

15. A winder having, in combination, 55 means forming a passageway for the thread, said passageway having a flaring entrance, a detector arranged to swing into engagement with the thread, and a hook located at one side of the passageway and rearwardly 60 of said entrance to keep the thread within reach of the detector.

16. A winder having, in combination, 65 means forming a passageway for the thread, a detector arranged to swing into engagement with the thread, and a hook at one side

of the passageway to keep the thread within reach of the detector.

17. A winder having, in combination, a 70 yarn - mass supporting lever, a projection fixed with relation to said lever, a movably mounted member, a spring tending to press said member against said projection, means for swinging the lever to raise said projection above said member, and means to lock said member against movement out of a position beneath the projection. 75

18. A winder having, in combination, a rotatory drum, a support in front of the drum, a lever pivoted on the support and normally extending rearwardly to support a 80 yarn mass on the drum, a projection fixed to said lever and extending rearwardly, a lever pivoted near its upper end, the upper portion of said second lever having a notch to receive said projection, a spring connected to the lower portion of the second lever, means for swinging the first lever upwardly to remove the projection from the notch, the projection being arranged to rest upon the upper end of the second lever, the first lever 90 being then free to swing upwardly and forwardly, and a handle on the lower portion of the second lever.

19. A winder having, in combination, a 95 yarn-mass rotator, a yarn-mass support, a pivoted detector to detect exhaustion of the thread being wound, a spring-pressed lever acting on said support to press the yarn mass against the rotator, mechanism controlled by the detector for moving the support away from the rotator, and means connected with the detector and arranged to be engaged by the lever for moving the detector into thread-receiving position.

20. A winder having, in combination, a 105 yarn-mass rotator, a support to hold a yarn mass in operative relation to the rotator, a stop for limiting movement of the yarn-mass support toward the rotator, and a yarn-mass gaging member movable through contact 110 with the yarn-mass to place the stop in operative position.

21. A winder having, in combination, a 115 yarn-mass rotator, a yarn-mass support, a detector to detect exhaustion of the thread being wound, means to hold the yarn mass and the rotator in contact with each other, and means controlled by the detector for separating the yarn mass and the rotator from each other, one of the last mentioned 120 two means being arranged to move the detector into thread-receiving position.

22. A winder having, in combination, a 125 yarn-mass rotator, a yarn-mass support, a detector to detect exhaustion of the thread being wound, means operating on said support to press the yarn mass against the rotator, and means controlled by the detector for moving the support to remove the yarn mass from the rotator, one of the last men- 130

tioned two means being arranged to move the detector into thread-receiving position.

23. A winder having, in combination, a rotatory drum, a support in front of the drum, 5 a lever pivoted on the support and normally extending rearwardly to support a yarn mass on the drum, a projection fixed to said lever and extending rearwardly, a second lever on the support, the upper portion of 10 the second lever having a notch to receive said projection, and a spring tending to move the second lever, the projection being adapted to rest upon the upper end of the second lever, the first lever being then free 15 to swing upwardly and forwardly.

24. A winder having, in combination, a rotatory drum, a lever for supporting a yarn mass on the drum, a projection fixed to said lever, a lever pivoted near its upper end, the upper portion of said second lever being 20 arranged to press against said projection, a spring connected to the lower portion of the second lever, means for swinging the first lever to move the projection out of position to be pressed by the second lever, and 25 a handle on the lower portion of the second lever.

In testimony whereof, I have hereunto set my hand.

HOWARD D. COLMAN.
